UNITED STATES PATENT OFFICE

2,154,610

ROPE FASTENER

Alexander L. Fleury, Milwaukee, Wis.

Application January 26, 1937, Serial No. 122,469

2 Claims. (Cl. 24—129)

My invention pertains to rope fasteners and more particularly to the type of fastener that may be employed on tow lines, tents, boats, or any other application where rope is used.

5 The objects of my invention is to provide a fastener that will permit a rope to be easily attached or detached without the use of a knot.

Another object of my invention is to provide such a device that will accomplish the purpose 10 for which it is intended without injuring the rope.

A still further object of my invention is to provide a device of the character described that is inexpensive to manufacture yet practical and 15 efficient in every detail.

Other and further objects of my invention will become more apparent as the description proceeds when taken in conjunction with the accompanying drawing in which

20 Fig. 1 is a perspective view of the device attached to the end of a rope.

Fig. 2 is a perspective view of the device having the rope attached and showing the manner in which a loop may be formed.

25 Fig. 3 is a plan view of the device showing the path of the rope when forming a loop.

Fig. 4 is a plan view of the fastener only, and

Fig. 5 is a fragmentary cross sectional view of the device as shown in Fig. 4 when taken at line 30 A—A.

Similar characters of reference indicate corresponding parts throughout the several views and referring now to the same the character 10 shows a body member consisting of an angular shaped 35 flat portion. There are members 11, 12, and 13 extending upward at right angle to the body 10 and radially formed to accommodate the rope. The member 12 disposed at a point midway between the members 11 and 13 projects outward 40 over a projecting ledge 14 forming a part of the body 10, while the members 11 and 13 project inwardly so that the depending ends extend over the body proper.

At one end of the body 10 and integral with 45 it is a U shaped shank portion 15 provided with projecting prongs 16. These prongs act as attaching means when formed around the circumference of the rope. At a point centrally disposed between the prongs 16 on the body of the 50 shank portion 15 is a ledge 17 over which the rope must be placed when engaging the shank portion 15. When the projecting prongs 16 are radially formed over the rope, this ledge 17 prevents the rope from disengaging the shank portion 55 15 when a pulling pressure is applied.

In operation the end of a rope is placed into the U shaped shank portion 15 over the ledge 17 so that the extreme end of the rope reaches the body section 10 as shown at 18. The projecting prongs 16 are then formed over the rope and being constructed as shown, the opposite points of the prongs engage one another, forming complete bands for retaining the rope. As these prongs 16 are forced into position it will cause the rope to engage the ledge 17 permitting the 10 rope to bulge upward so as to prevent slipping from the shank 15.

The rope may then be looped around the object to be held and as it is passed parallel to the members 11 and 13 it may be forced over the member 15 12 causing an irregular path and preventing the rope from slipping due to the frictional contact on the members due to their irregular relation to one another.

It is obvious to anyone familiar with the art 20 that knots in rope are a source of annoyance and trouble and it is very often impossible to open a knot after it has been securely set due to an extreme pull in service. The device illustrated, specified, and claimed eliminates this unnecessary 25 trouble and delay by permitting the user to quickly disengage the rope or take up the slack without any loss in time or equipment.

In the chosen embodiments of my invention, exemplified by the accompanying drawing, there 30 are present certain novel refinements and improvements not heretofore disclosed in the prior art, and which will be hereinafter more fully referred to and specifically pointed out in the appended claims.

35 Having thus described my invention, what I claim and desire to secure by Letters Patent in the United States, is:

1. A rope fastening device of the character described comprising an elongated flat body portion, upwardly projecting end members extending from the outer edge of said body portion, an upwardly projecting center member extending inwardly from the outer edge of said body portion and spaced outward from the parallel path of 45 said end members, all of said members having an arced contour, the contour of said center member being opposite from that of said end members, and said body member having a portion offset from the longitudinal plane of the 50 body, clamping members on the offset portion arranged opposite one another to provide means for fastening the end of a rope when said clamping members encircle said rope.

2. A device of the character described com- 55

prising an elongated body, arced contact members projecting upward at right angles to said body at each end and near the center, said end members having their arced contours opposite from said center member, said center member being positioned outward from the parallel path of said end members and inward from the outer edge of said body, a U-shaped shank member

integrally connected to one end of said body, the shank being offset from the longitudinal plane of the body, clamping members arranged in opposite relation to one another on said shank member, and said shank member having a projecting ledge formed in the bight portion of said shank member between said clamping members. 5

ALEXANDER L. FLEURY.
